United States Patent Office

Des. 179,026
Patented Oct. 23, 1956

179,026

TEXTILE FABRIC OR SIMILAR ARTICLE

Thomas Nelson, Boston, Mass., assignor to American Twine & Fabric Corporation, Boston, Mass., a corporation of New Hampshire

Application February 16, 1956, Serial No. 40,182

Term of patent 7 years

(Cl. D92—1)

The single figure is a plan view of a textile fabric or similar article showing my design.

I claim:

The ornamental design for a textile fabric or similar article, substantially as shown.

References Cited in the file of this patent

UNITED STATES PATENTS

D. 88,519	Frambach	Dec. 6, 1932
D. 89,402	Marks	Mar. 7, 1933
D. 120,799	Carragher et al.	May 28, 1940
D. 177,094	Holt	Mar. 13, 1956